UNITED STATES PATENT OFFICE.

MOSES E. TEBO, OF LAUREL, MONTANA.

BATH FIXTURE.

Application filed July 9, 1923. Serial No. 650,369.

To all whom it may concern:

Be it known that I, MOSES E. TEBO, a citizen of the United States, residing at Laurel, in the county of Yellowstone and State of Montana, have invented certain new and useful Improvements in Bath Fixtures, of which the following is a specification, reference being had to the accompanying drawings.

10 This invention relates to certain improvements in bath fixtures and it is an object of the invention to provide a novel and improved device of this general character especially designed and adapted for use in the 15 washing of a back.

It is also an object of the invention to provide a novel and improved device of this general character which is employed as an attachment for use in connection with a 20 bath-tub, and wherein means are provided for effectively maintaining the device in applied or working position.

An additional object of the invention is to provide a novel and improved device of 25 this general character embodying a member supported for reciprocatory movement, said member being adapted to carry a cleaning element and wherein means are provided for imparting the required movement to the 30 member.

The invention consists in the details of construction and in the combination and arrangement of the several parts of my improved bath fixture whereby certain important advantages are attained and the device rendered simpler, less expensive and otherwise more convenient and advantageous for use, as will be hereinafter more fully set forth.

40 The novel features of my invention will hereinafter be definitely claimed.

In order that my invention may be the better understood, I will now proceed to describe the same with reference to the accompanying drawings, wherein:—

45 Figure 1 is a view partly in section and partly in elevation illustrating a bath fixture constructed in accordance with an embodiment of my invention and in applied position;

50 Figure 2 is a view in perspective of the supporting plate and certain of the parts directly associated therewith;

55 Figure 3 is a view in perspective of the reciprocating member or plate as herein disclosed;

Figure 4 is a fragmentary view in top plan of the holding rod as herein disclosed;

Figure 5 is a view partly in section and partly in top plan of the device as illustrated in Figure 1;

Figure 6 is a fragmentary view partly in section and partly in elevation illustrating in detail one of the adjustable arms as herein set forth;

Figure 7 is a fragmentary elevational view illustrating an adjustable arm constructed in accordance with a further embodiment of my invention.

As herein disclosed, my improved device 70 comprises an arcuate member 1 substantially semi-circular in form and which has each of its extremities provided with a cross head 2 whereby the member 1 may be riveted or otherwise secured to the central portion of 75 a plate 3.

The plate 3 is of desired dimensions and has its side portions defined by the reverted flanges 4, each of said flanges being provided with a series of longitudinally spaced 80 openings 5 for a purpose to be hereinafter more particularly referred to.

A second member or plate 6 is adapted to overlie the plate 3 and the side marginal portions of said plate 6 are defined by the 85 inwardly directed flanges 7 adapted to overlap and have close contact with the flanges 4 of the plate 3. The flanges 7 are continued by the inwardly directed flanges 8 adapted to straddle the free longitudinal 90 marginal portions of the flanges 4 whereby the plate or member 6 is supported for sliding movement by the plate 3. The flanges 7 and 8 are also provided with openings 9. These openings are adapted to be selectively 95 brought into register with the openings 5 of the plate 3 and through said openings is adapted to be disposed a rod 10 whereby the plates 3 and 6 will be locked against relative movement and with the plate 6 held in 100 a desired adjusted position with respect to the plate 3.

The central portion of the member 1 is provided with an inwardly directed arm 11 provided in its extended portion with a sleeve 12 the axis of which being disposed in the same general direction as the longitudinal axis of the plate 3 or in the same general direction in which the plate 6 reciprocates.

110 Slidably disposed through the sleeve 12 is a post 14. Secured to one end of the post

is a suction cup 15 preferably of rubber, while the opposite end portion of the post 14 is provided with a goose neck 16. Engaged with the free extremity of the goose neck 16 is a pulley or sheave 17. The sleeve 12 and the post 14 are adapted to be adjusted one with respect to the other along the post 14 and the sleeve 12 as herein disclosed is held by the binding screw 18 threaded through a wall of the sleeve for requisite contact with the post 14.

Connecting the end portions of the member 1 but spaced from the associated plate 2 is a rod 19 to the central portion of which 15 is operatively engaged the terminals of a retractile spring 20, the opposite terminal of said spring is operatively connected as at 21 with an offset head 22 of a rod 23. The rod 23 is secured to an end portion of 20 the plate 6 and extends therebeyond. Also secured to the head 22 is a flexible member 24 passing over the pulley or sheave 17 and terminating in a hand grasp 25. Upon imposing pull upon the member 24 the plate 25 6, with the rod 10 removed moves the plate 6 in one direction with respect to the plate 3, such movement placing the spring 20 under tension so that upon release of the pull, the spring 20 will operate automatically to move 30 the plate 6 in the opposite direction. It is therefore, to be obvious, that by intermittent pull upon the flexible member 24 the plate 6 may be reciprocated as desired.

As herein disclosed the cleaning element 35 C comprises a brush held to the plate 6 by the clips 26, each of the clips 26 has one end portion operatively engaged with the back of the brush while the opposite end portion of said clip is freely disposed through a loop 27 properly positioned upon a flange 7 and engaged with said end portion of the clip 26 outwardly of the loop 27 and coacting with said loop is a holding nut 28. In lieu of the brush a cloth or 45 other preferred element may be employed.

My improved device is adapted to be employed in connection with a bathtub and when in working position the post 14 is positioned within an end portion of a tub T 50 with the cup 15 pressed down on the bottom of the tub to obtain a vacuum hold for the lower end of the post 14. To further maintain the device in applied or working position I provide the holding members or arms H.

Each of the holding members or arms H as herein disclosed comprises two telescopically engaged sections 29 and 30 held in desired adjusted relation by a set screw 31 or the like. The outer end portion of the inner section 29 is bifurcated as at 32 to straddle the member 1. The kerf of the bifurcation 32 is bridged by a bolt 33 disposed through the forks of the bifurcation 60 and when the holding member or arm H is

in applied position said bolt 33 seats within a recess 34 in the inner marginal portion of the member 1 and properly positioned. The outer extremity of the section 30 of each of the holding members or arms H is 75 hingedly connected, as at 35 with a hook member 36, said hook member engaging from above the rim 37 of the tub. The bill of the hook member 36 has threaded therethrough a clamping or set screw 38 which is adapted to engage the rim 37 from below whereby the outer end portion of the member or arm H is effectively maintained in working engagement with the rim 37. The shank of the hook member 36 is preferably 80 cased within a rubber sheet 39 or the like.

In Figure 7 I illustrate an embodiment of my invention wherein the holding member or arm H' comprises two sections the opposed ends of which being adjustably connected by a turnbuckle 40 and wherein the outer or free end of the section 29' is provided with a split loop 41 for coaction with the member 1, said loop 41 being maintained closed by a screw 42 or the like.

The operation of my device is believed to be clearly apparent from the foregoing description although it is to be understood that the rod 10 hereinbefore referred to is only employed when the cleaning element 95 C is adapted to be maintained in a fixed position and the spring 20 and flexible member 24 are not employed. It is also to be understood that the cleaning element may comprise a folded towel if preferred.

From the foregoing description it is thought to be obvious that a bath fixture constructed in accordance with my invention is particularly well adapted for use by reason of the convenience and facility with 100 which it may be assembled and operated, and it will also be obvious that my invention is susceptible of some change and modification without departing from the principles and spirit thereof and for this reason 110 I do not wish to be understood as limiting myself to the precise arrangement and formation of the several parts herein shown in carrying out my invention in practice except as hereinafter claimed.

I claim:

1. A bath fixture comprising, in combination, a post, a suction cup at one end of the post, a plate operatively engaged with the post and supported thereby, a second plate slidably engaged with the first named plate, a cleaning element carried by the second plate, and holding members operatively engaged with the first named plate.

2. A bath fixture comprising, in combination, a post, a suction cup at one end of the post, a plate operatively engaged with the post and supported thereby, a second plate slidably engaged with the first named plate, a cleaning element carried by the sec- 130

- ond plate, holding members operatively engaged with the first named plate, and means carried by the holding members for engagement with the rim of a tub.
- 5 3. A bath fixture comprising a post, a plate operatively engaged therewith and supported thereby, a plate slidably engaged with the first named plate, a cleaning element carried by the second plate, manually

operated means for imparting movement to 10 the second plate in one direction, and means coacting with both of the plates for automatically moving the second plate in the opposite direction.

In testimony whereof I hereunto affix my 15 signature.

MOSES E. TEBO.
